(57) **CLAIM**

The ornamental design for a splicing toy, as shown and described.

DESCRIPTION

FIG. 1 is a perspective view of a splicing toy showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view showing the splicing toy in a use state.
The broken lines in FIG. 8 depicting another two splicing toys form no part of the claimed design.**1 Claim, 8 Drawing Sheets**FIG. 1

FIG. 2

FIG. 3

FIG. 4

FIG. 5

FIG. 6

FIG. 7

FIG. 8
